UNITED STATES PATENT OFFICE

2,258,338

MEANS FOR CONTINUAL DISPENSATION OF
LIQUID AT A CONTROLLED RATE

Robert N. Park, Los Angeles, Calif.

Application December 19, 1939, Serial No. 309,991

6 Claims. (Cl. 221—97)

My invention relates to liquid dispensing devices with special reference to devices for supplying liquid continually at a relatively slow predetermined rate. My invention may be employed for various purposes in various fields and will be found applicable to many continuous manufacturing procedures. An immediate use contemplated is to dispense reagents in flotation methods of treating ore, and I elect to direct the present disclosure specifically to a device designed for such use. That the invention is applicable to other devices for other specific purposes will be obvious.

A typical flotation process requires continual delivery to a flotation unit of liquid chemicals or reagents at a constant predetermined rate, a rate so low that it may be conveniently expressed in drops per minute. Constant accuracy is required, neither too much nor too little of the liquid in any unit of time. The device must, then, not only be inherently accurate in its operation, but must also be designed to function accurately regardless of changes in the viscosity of the liquid with changing temperature conditions. Such a device must be capable of operation for days without attention and must not require highly skilled technicians for service or repair. It must not only be dependable and foolproof, but must also be easily adjustable to vary the rate of fluid dispensation.

The general object of my invention is to meet the above requirements for such a device in a simple but efficient construction. A further object of the preferred form of my invention is to provide a device that operates at constant speed, but is nevertheless adjustable in its rate of output.

The invention is characterized by the conception of continually releasing the liquid in drops in a progressive manner over a dripping zone in repeated operating cycles and providing liquid-receiving means that is adjustable over the dripping zone to receive for dispensation any desired portion of the dripped liquid. One of the more specific objects of my invention is to provide a suitable structural arrangement incorporating this conception.

Other objects and advantages of my invention will be apparent from the following detailed description, taken with the accompanying drawings.

In the drawing, which is to be taken as illustrative only:

Fig. 1 is a longitudinal section taken as indicated by the line 1—1 of Fig. 2;

Fig. 2 is a transverse section taken as indicated by the line 2—2 of Fig. 1;

Fig. 3 is a fragmentary plan view of the device; and

Fig. 4 is a fragmentary section on an enlarged scale showing the construction of a dipper element employed in the combination.

In the drawing, a tank, generally designated 10, constitutes a supply reservoir containing a quantity of liquid 11 that is to be dispensed by the apparatus. The tank has a bottom 12, four side walls 13, and a rim 14. A constant-level reservoir, generally designated 15, is provided in combination with the tank 10 and may be supported by a pair of posts 17 in the form of metal rods threaded into bosses 18 in the tank bottom 12. This second reservoir 15 has an overflow port 19 that drains into the tank 10 and has an arcuate bottom wall 20 immersed in the body of supply liquid 11.

The preferred form of my invention includes a countershaft 22 mounted in some suitable manner across both the tank 10 and the upper reservoir 15. In the particular construction shown in the drawing, a bearing collar 23 secured to the tank rim 14 by cap screws 24 on one side of the tank contains a roller bearing 25 for the countershaft 22, and on the other side of the tank a second bearing collar 26, likewise secured by cap screws 27, embraces a second roller bearing 28 for the countershaft.

Keyed to the end of the countershaft 22 outside the tank 10 is a suitable pulley 30 driven by a belt 31 in a clockwise direction as viewed in Fig. 1. Means for continually replenishing the upper reservoir 15 from the tank 10 may comprise two replenishing receptacles 32 carried respectively by two arms 33 that extend diametrically from a hub 34, the hub being keyed to the countershaft 22. As the countershaft rotates in the normal operation of the apparatus, the two replenishing receptacles 32 move in an orbit that passes under the arcuate bottom wall 20 of the upper reservoir, the replenishing receptacles dipping quantities of liquid from the tank 10 at the bottom of their orbit and emptying their contents into the upper reservoir 15 in traversing the upper part of their orbit. The replenishing rate provided by the capacity of the two receptacles 32 exceeds the maximum dispensing rate contemplated in the operation of the apparatus so that the upper reservoir 15 is maintained at a constant level determined by the location of the overflow port 19.

Also keyed to the countershaft 22 is a rotary

member in the form of a disc 35 that is partially submerged in the liquid body 36 in the upper reservoir 15, the disc being adapted in some suitable manner to carry a variable number of receptacles or dippers 40. These dippers may have, for example, a capacity of five to fifteen drops of liquid. In the particular construction shown, each of the dippers 40 has a threaded stem 41 screwed into an arm 42 and the arm is mounted on the face of the disc 35 by means of a screw 43 extending through a suitable countersunk bore 44 in the disc. The drawing shows four such arms 42 each with a single dipper 40 and a fifth arm 42a that is longer than the other arms and has not only a dipper 40 in the same relative position as the other dippers 40, but also a second and outer dipper 40a, as best shown in Fig. 3. It will be noted that there is an excess number of countersunk bores 44 so that additional dipper-bearing arms may be added to the disc 35 as required.

As the disc 35 rotates, the dippers are successively immersed in the upper liquid body 36 and successively emerge with quantities of the liquid that drip in drops from the dippers as the dippers move to the upper portion of their circular paths. Since the dippers moving upward from the constant-level reservoir 15 are both progressively tilted and carried through space, they drip their contents drop by drop progressively across what may be termed a "dripping zone" of somewhat less extent than the diameter of the circular paths. Since all of the dippers 40 are in a common plane, they have a common dripping zone which may be termed conveniently the "inner dripping zone," and the dipper 40a empties progressively across a second dripping zone which may be termed the "outer dripping zone."

In one practice of my invention, the rate at which liquid is dispensed by the apparatus is controlled simply by varying the angular disposition of the various dippers 40 relative to the disc 35, since the quantity of liquid lifted by each dipper is determined by the angle of the dipper at the moment the dipper emerges from the liquid body 36. In the preferred practice of my invention, however, the procedure for varying the rate at which the liquid is dispensed is based on the fact that the liquid is released from the successive dippers in successive drops at progressively advanced points across the two dripping zones. By providing adjustable liquid-receiving means in one or both of the dripping zones to be effective over variable portions of the dripping zone, I may retrieve variable portions of the dripped liquid for dispensing from the apparatus.

Any suitable liquid-receiving arrangement may be employed that is variable in effective extent relative to the dripping zone, but the following arrangement will be found to have a number of distinct advantages. A fixed arm 47 attached to the bearing collar 26 by suitable screws 48 holds a drip apron 50 that extends across both the inner and outer dripping zones. The drip apron 50 is provided with a rib 51 along each of its longitudinal edges to confine the dripped liquid to the upper surface of the apron and slopes downward to a transverse drain trough 52 integral therewith. The liquid received by the drain trough 52 flows into a dispensing tube 53 that conducts the retrieved liquid to a dispensing zone. In the present embodiment of the invention the dispensing zone is, of course, a

flotation unit (not shown) adjacent to the dispensing apparatus.

In the particular construction shown in the drawing, a second liquid-receiving means is provided in each of the dripping zones to divert the dripped liquid back into the upper reservoir 15. Thus, a drip apron 55 in the inner dripping zone is mounted on the end of an arm 56 to swing about the axis of the countershaft 22, and a second drip apron 57 in the outer dripping zone is carried by a second arm 58 to rotate about the same axis. When either of the two aprons 55 and 57 is in its uppermost position, the position of the apron 57 in Fig. 1, the apron completely masks the underlying stationary apron 50 in that dripping zone and causes all of the dripped liquid in the zone to flow downward over the outer surface of the movable apron into the upper reservoir 15. Each of the aprons 55 and 57 is provided with a pair of marginal ribs or flanges 59 to prevent the liquid thereon flowing laterally onto the underlying stationary drip apron 50.

When either of the two adjustable aprons 55 and 57 is at its lowermost position, the position of the apron 55 in Fig. 1, it completely unmasks the stationary apron 50 in the corresponding dripping zone so that all of the dripped liquid in that zone within the range of the stationary apron reaches the drain trough 52 and flows out the dispensing tube 53. Preferably, each of the movable aprons 55 and 57 has a shoulder 60 on its inner side adapted to abut the rim of the drain trough 52 as a stop to limit downward movement of the movable apron. Preferably, each of the aprons 55 and 57 has an auxiliary liquid-receiving surface 61 on its inner side bounded by two liquid-confining flanges 62 and this auxiliary surface is so disposed that when the shoulder 60 is against the drain trough 52 the surface 61 inclines outward from the drain trough to direct dripped liquid into the drain trough and thus increase the quantity of dripped liquid retrieved for dispensing through the tube 53.

For mounting the two aprons 55 and 57 to rotate about the axis of the countershaft 22, I provide a fixed tube 65 surrounding the countershaft, the tube being threaded into the bearing collar 26 and having an annular flange 66 at its free end. The apron arm 56 of the inner dripping zone is integral with a sleeve 67 that rotatably embraces the fixed tube 65 and is normally releasably secured against rotation by a suitable set-screw 68. In like manner the apron arm 58 of the outer dripping zone is integral with a second sleeve 69 that rotatably embraces the first sleeve 67 and is normally anchored against rotation relative thereto by a suitable set-screw 70. A washer 71 also embracing the inner sleeve 67 may separate the two apron arms 56 and 58. It is apparent that rotational adjustment of the inner sleeve 67 will vary the disposition of both the aprons 55 and 57 simultaneously, while adjustment of the outer sleeve 69 provides independent adjustment for the drip apron 57, so that the two drip aprons 55 and 57 may be placed in any relationship desired within their range of movement.

The operation of my apparatus may be readily understood from the foregoing description. In a typical installation the disc 35 is rotated at a constant speed of one complete rotation per minute. In any case the speed is slow enough to permit each of the dippers 40 to drain in drops

completely within the period it traverses the corresponding dripping zone, regardless of how viscid the liquid may become in cool weather. For example, if each of the dippers **40** in the angular disposition shown in Fig. 1 carries ten drops of liquid upward from the liquid body **36** and releases the ten drops of liquid successively as it passes across the inner dripping zone, there will be fifty drops per minute deposited in the inner dripping zone and all of the fifty drops will be received either on the fixed drip apron **50** or on the auxiliary receiving surface **61** of the inner movable apron **55**, the inner apron being in the disposition shown in Fig. 1. The outer dipper **40a**, the only dipper in the outer dripping zone, also catches up ten drops of the liquid and distributes the ten drops in the course of one rotation of the disc **35**. Since the outer movable apron **57** is in the uppermost position shown in Fig. 1, it completely masks the fixed apron **50** in the outer dripping zone and diverts all ten drops from the outer dipper **40a** away from the drain trough **52** back into the upper reservoir **15**. With the described adjustment of the two aprons **55** and **57**, then, the apparatus will dispense fifty drops per minute through the dispensing tube **53**.

If it is desired to raise the dispensing rate from fifty or more up to sixty drops per minute, the movable apron **57** in the outer dripping zone is swung counter-clockwise from its uppermost position to unmask a sufficient portion of the underlying fixed drip apron **50** to receive the desired number of additional drops from the outer dipper **40a**. It is apparent that the outer drip apron **57** may be swung downward to cause any number of the ten drops from the outer dipper **40a** to be carried into the drain trough **52**. If the quantity dispensed per minute is to be increased by more than ten drops over the fifty drops per minute provided by the original setting, another dipper **40** will be added to operate in the inner dripping zone. If the number of drops dispensed per minute is to be decreased by more than ten from the original setting of fifty drops per minute, either of two procedures may be followed. In the first procedure, one of the dippers **40** is removed from the disc, leaving only four dippers **40** operative in the inner dripping zone and any further adjustment required is achieved by changing the disposition of the outer movable apron **57**. In the alternate procedure for reducing the number of drops dispensed per minute, only the inner apron **55** is manipulated, the inner apron being swung upward or clockwise to reduce the effective area of liquid-receiving surfaces in the inner dripping zone.

While constant speed of operation is employed in the preferred form of my device, it does not characterize all forms. Obviously, in some practices of my invention, the speed of operation may be varied to vary the rate at which the liquid is dispensed.

The preferred form of my invention described in specific detail herein will suggest to those skilled in the art various changes, modifications, and substitutions that do not depart from my underlying concept, and I reserve the right to all such changes, modifications, and substitutions that properly come within the scope of my appended claims.

I claim as my invention:

1. An apparatus for dispensing liquid comprising in combination: a liquid reservoir; a rotary carrier above said reservoir; at least one receptacle mounted on said carrier to be moved there-

by in a circular path, said receptacle being mounted at an angle to cause the receptacle to dip liquid from said reservoir at a lower portion of its circular path and to spill the liquid across a dripping zone extending over a substantial range of the upper portion of the circular path, said carrier being adapted to rotate sufficiently slowly to cause the liquid to be discharged in discrete drops distributed progressively over the dripping zone; and means to receive and dispense the dripped liquid, said receiving means being adjustable with respect to its effective extent across said zone in the direction in which said drops are progressively distributed.

15 2. An apparatus for dispensing liquid comprising in combination: a liquid reservoir; at least one receptacle for conveying liquid from said reservoir; means adapted to carry said receptacle in a closed path through successive cycles to cause the receptacle to dip liquid from said reservoir and to spill the liquid across a dripping zone, said carrying means operating at a slow rate to spill the liquid in discrete drops progressively spaced across said dripping zone; liquid-receiving means in said dripping zone adapted to direct liquid back to said reservoir; and liquid-receiving means in said zone adapted to direct liquid to a dispensing zone, at least one of said liquid-receiving means being adjustable along the line of the progressive spacing of said drops to vary the ratio of the numbers of said drops directed to said dispensing zone to the number of drops directed back to said reservoir.

30 3. An apparatus for dispensing liquid comprising in combination: a liquid reservoir; means adapted to drip successive quantities of liquid from said reservoir in successive discrete drops spaced progressively across a dripping zone; and means adjustable along the line of dripping progression across said dripping zone to divert a variable number of said spaced drops from said dripping zone for dispensation.

35 4. An apparatus for dispensing liquid comprising in combination: a liquid reservoir; a rotary carrier; at least one receptacle on said carrier in fixed relation thereto for movement in a circular path to dip liquid from said reservoir at a lower portion of said path and to distribute the dipped liquid at an upper portion of said path, said carrier rotating sufficiently slowly to release the liquid in discrete drops spaced progressively along said upper portion of the path; and means adjustably movable under said upper portion of the circular path in a direction to intercept a varying number of said drops to vary the number of said drops dispensed.

50 5. An apparatus for dispensing liquid comprising in combination: a liquid reservoir; a rotary carrier; at least one receptacle on said carrier in fixed relation thereto for movement in a circular path to dip liquid from said reservoir at a lower portion of said path and to distribute the dipped liquid at an upper portion of said path, said carrier rotating sufficiently slowly to release the liquid in discrete drops spaced progressively along said upper portion of the path; and means within the space surrounded by said path under said upper portion of the path to divert some of said drops for dispensation, said means being adjustable in the plane of said circular path to vary the number of said drops dispensed.

55 6. An apparatus for dispensing liquid comprising in combination: a liquid reservoir; a rotary carrier above said reservoir; at least one

receptacle on said carrier for movement in a first circular path to dip liquid from said reservoir and to spill the liquid across a first dripping zone; at least one receptacle on said carrier for movement in a second circular path spaced laterally from said first circular path to dip liquid from said reservoir and to spill liquid across a

second dripping zone; means to divert dripped liquid from said first dripping zone to a dispensing zone; and adjustable means to divert various portions of the dripped liquid from said second dripping zone to a dispensing zone.

ROBERT N. PARK.
